CLAIM

We claim the ornamental design for a table, as shown and described.

DESCRIPTION

FIG. 1 is a top-right rear perspective view of a table; FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a bottom-left perspective view thereof.

The dash-dot broken lines in FIGS. 1-8 illustrate boundaries that form no part of the claimed design, and the uniform broken lines illustrate portions of the table that form no part of the claimed design.

1 Claim, 6 Drawing Sheets
